UNITED STATES PATENT OFFICE.

ANDREW L. HANSON, OF CUMBERLAND CENTER, MAINE.

DARNING FORM.

1,404,763.

Specification of Letters Patent. Patented Jan. 31, 1922.

Application filed May 31, 1919. Serial No. 300,815.

To all whom it may concern:

Be it known that I, ANDREW L. HANSON, a citizen of the United States, residing at Cumberland Center, in the county of Cumberland and State of Maine, have invented new and useful Improvements in Darning Forms, of which the following is a specification.

My present invention pertains to forms 10 for use in darning, and is designed more especially for the darning of the foot portions of stockings.

The object of the invention is to provide an adjustable darning form—i. e., a darning 15 form that is adapted to be put in the foot form of a stocking with facility and then extended as to length, with a view to distending the foot portion and maintain it in foot form during the darning operation.

20 With the foregoing in mind, the invention in all of its details will be fully understood from the following description and claims when the same are read in connection with the drawings, accompanying and forming 25 part of this specification, in which:

Figure 1 is a side elevation of my novel form in closed or contracted state.

Figure 2 is a plan view of the same.

Figure 3 is a longitudinal vertical section 30 showing the form as extended or increased in length.

Figure 4 is a top plan view of the extended form.

Figure 5 is an enlarged transverse section 35 taken through the form, and hereinafter specifically referred to.

Similar numerals of reference designate corresponding parts in all of the views of the drawings.

40 Among other elements my novel form comprises a heel member 1 and a toe member 2. These members are preferably, though not necessarily, hollow, and made of sheet-metal or other material suitable to their 45 purpose.

In combination with the hollow member 1 and toe member 2, I employ a metallic oval continuance loop 3, preferably of wire, and possessed of resiliency. The said metallic 50 loop 3 is held to the members 1 and 2 through the medium of retaining guides 4 which are preferably, though not necessarily, in the form of metallic loops, as shown, connected to the inner surface of the members 1 and 2 55 so as to slide upon the side portions of the loop 3.

Referring now to Fig. 3 I also slightly groove the curved ends of loop 3, as shown at 3⁴, to enable said ends to move and be guided under flat metal straps longitudinally extended and attached to the interior of said members and arranged to rest in said groove. It will also be appreciated that the springing of the wire loop 3 together with the interposition of the ends of the said wire 60 loop between the members 1 and 2 and the straps 5, will hold the members 1 and 2 against accidental movement on the loop 3 during darning of holes in the toe and heel portions of a sock or stocking. I would have 65 it understood, however, that when the members 1 and 2 are solid, the straps 5 may be altogether omitted.

Upon the completion of the darning operation the form may obviously be readily 70 shortened or lengthened by pressure on the ends of the form while in the stocking, thus moving one end of the form relative to the other on the loop and in substantially the plane of the loop.

Having described my invention, what I 75 claim and desire to secure by Letters-Patent, is:

1. A form comprising members one of which is movable away from and toward the other, a member connecting the first-named members and upon which the said movable member may be moved longitudinally toward and from the other member, and a longitudinal strap carried by the movable member 85 and arranged at the opposite side of a portion of the connecting member, with reference to a portion of the movable member, and frictionally bearing against the connecting member.

2. A darning form comprising two end members with openings in their adjacent ends, a connecting oval loop having its curved ends loosely mounted in said open ends and means for slidably connecting said 90 members to the sides of said loops.

3. A darning form comprising two members with openings in their adjacent ends, a connecting oval loop having its curved ends loosely mounted in said open ends, means 105 for connecting said members to the sides of said loop, and means for yieldingly bonding the curved ends of the loop to the bottom of the members.

In testimony whereof I affix my signature. 110

ANDREW L. HANSON.
